UNITED STATES PATENT OFFICE.

WILLIAM A. HATCHER, OF CLEVELAND, OHIO, ASSIGNOR TO THE BREW-HATCHER COMPANY, OF CLEVELAND, OHIO, A CORPORATION OF OHIO.

LUBRICATOR.

SPECIFICATION forming part of Letters Patent No. 791,418, dated May 30, 1905.

Application filed April 13, 1904. Serial No. 202,941.

To all whom it may concern:

Be it known that I, WILLIAM A. HATCHER, a citizen of the United States of America, residing at Cleveland, in the county of Cuyahoga and State of Ohio, have invented certain new and useful Improvements in Lubricators; and I hereby declare the following to be a full, clear, and exact description of the invention, such as will enable others skilled in the art to which it pertains to make and use the same.

My invention relates to improvements in lubricators, and pertains more especially to a lubricator comprising a lubricant-receiving receptacle provided at its lower end with several discharge-ducts arranged a suitable distance apart and in line laterally and means whereby the said ducts are successively supplied with grease or lubricant.

The primary object of this invention is to conveniently apply adequate power to the lubricant-feeding head or piston on top of the grease or lubricant within the aforesaid receptacle to adequately and positively feed lubricant from the said receptacle to each of the aforesaid ducts and to render the said receptacle chargeable with facility.

Another object is to construct a lubricator of the character indicated which is simple and durable in construction, conveniently operated, and reliable in its operation.

With these objects in view my invention consists in certain features of construction and combinations and arrangement of parts hereinafter described, and pointed out in the claims.

In the accompanying drawings, Figure 1 is a side elevation, largely in central section, of a lubricator embodying my invention and shows the lubricator connected with several lubricant-conducting pipes. Fig. 2 is a side elevation of the externally-screw-threaded gear-bearing shaft employed in actuating the lubricant-feeding piston or movable pressure-exerting head of the lubricator and shows the said head ready to be removed upwardly from the lower end of the shaft. Fig. 3 is a vertical section on line 3-3, Fig. 2, looking in the

direction indicated by the arrow. Fig. 4 is a top plan in section on line 4-4, Fig. 1. Fig. 5 is a top plan in section on line 5-5, Fig. 1. 50

Referring to the drawings, A indicates a vertically-arranged receptacle which is provided interiorly with a lubricant-receiving chamber a, which is circular in cross-section. Within and centrally of the chamber a (see 55 Fig. 1) is a vertically-arranged tubular shaft B, and a bevel-gear b is formed upon the lower end of and integral with the said shaft. The bore 10 of the shaft B is cylindrical in cross-section and is loosely engaged at its 60 lower end by an upwardly-projecting vertically-arranged corresponding cylindrical bearing-forming lug 12, which is formed upon and centrally of the top of a horizontally-arranged box 13, which is integral with the receptacle A and arranged below the gear b. The box 13 affords bearing to a correspondingly-arranged shaft C, which has also bearing in two boxes 14 and 19, which are formed integral with the receptacle A and arranged at 70 and a suitable distance from opposite ends, respectively, of the central box 13. 65

The shaft B rests at its lower end upon the box 13 around the bearing 12, and the gear b is in mesh with the bevel-pinion c, operatively 75 mounted on the shaft C between the central box 13 and the end box 19, and the chamber a is enlarged downwardly, as at 15, between the said boxes and around the said shaft to accommodate the location of the said pinion. 80

The shaft C extends through the end boxes 14 and 19 and is operatively provided at the outer end of the box 19 with a hand-wheel C' for turning the shaft. The receptacle A is provided at its upper end and exteriorly with 85 screw-threads engaged by corresponding screw-threads formed upon and interiorly of the depending annular flange d of a cap D, which closes the said receptacle. The cap D is provided at its under side and centrally with a depending bearing-forming cylindrical lug 16, which projects into and snugly but easily fits within the bore 10 of the shaft B and is arranged in line endwise with the lug 90

12. By the construction hereinbefore described it will be observed that the lugs 12 and 16 afford lateral bearing to the shaft P.

The piston or head G is mounted upon the shaft B and has a hub or centrally-located sleeve g embracing the said shaft, which sleeve is provided interiorly with screw-threads engaging with screw-threads formed upon the shaft. The shaft B is screw-threaded approximately its entire length. The head G fits snugly but easily within the chamber a and is movable, as will hereinafter appear, endwise of the said chamber. The head G is prevented from turning with the shaft B, so that the said head will descend or ascend, according as the shaft is turned in the one or the other direction.

The means employed for preventing turning of the head G with the shaft B (see Figs. 2 and 4) comprises, preferably, a metal strip 17, which is arranged vertically within and secured to the surrounding wall of the chamber a. The member 17 extends the entire length of the path of the head G and engages with a recess 18, formed in the said head, and thereby prevents the said head from turning upon the shaft B during the rotation of the said shaft.

The shaft C is provided interiorly with a passage-way-forming bore 20, which extends longitudinally of the shaft from within the hand-wheel-bearing end portion of the shaft to the outer end of the box 14, where it is closed by an internally-screw-threaded cap e, which embraces the outer end of the said box and engages corresponding screw-threads formed upon and exteriorly of the said box. The shaft C is provided at the outer end of the box 19 with an external annular shoulder 22, which is overlapped by the inner end of a ring f, which loosely embraces the shaft C. The ring f is provided at its inner end with an internally-screw-threaded annular flange 23, engaging corresponding screw-threads formed upon and exteriorly of the outer end portion of the box 19. It will be observed, therefore, that the cap e and the ring f prevent endwise displacement of the shaft C.

The receptacle A is provided at its lower end and next below the shaft C with four downwardly-discharging ducts 24, 25, 26, and 27, arranged a suitable distance apart longitudinally of the said shaft and in line laterally, as shown in Fig. 1. The grease or lubricant supplied by my improved lubricator is forced from within the chamber a to and through the ducts 24, 25, 26, and 27 into the tubes or pipes P employed in conducting lubricant to axles or bearings to be lubricated. As shown in Fig. 1, the ducts 25 and 26 are formed at the bottom of the central box 13 and the ducts 24 and 27 are formed at the bottom of the boxes 14 and 19, respectively.

The downward enlargement 15 of the cham-

ber a is in communication with the interior passage-way 20 of the shaft C through two ports 28, formed in the surrounding wall of the said passage-way at opposite sides, respectively, of the said shaft, as shown in Fig. 5. The chamber a is also enlarged downwardly around the shaft C, as at 30, and the said downward enlargement 30 of the said chamber is in communication with the interior passage-way 20 of the shaft C through two ports 32, formed in the surrounding wall of the said passage-way at opposite sides, respectively, of the shaft. It will be observed that the interior passage-way 20 is continually in communication with the chamber a. The shaft C is provided also in the surrounding wall of its interior passage-way 20 with as many ports as there are discharge-ducts leading from the lubricator. The shaft C of the lubricator illustrated is provided, therefore, with four ports 34, 35, 36, and 37, adapted to register with the ducts 24, 25, 26, and 27, respectively. The ports 34, 35, 36, and 37 are arranged, therefore, at suitable intervals longitudinally of the shaft C and are spaced, furthermore, equidistantly circumferentially of the said shaft. The arrangement of the ports 34, 35, 36, and 37 relative to the ducts 24, 25, 26, and 27 is such that the ports 34, 35, 36, and 37 shall during the rotation of the shaft C successively communicate with the different ducts 24, 25, 26, and 27, respectively.

To facilitate the distribution of the lubricant within the passage-way 20, the ports 28 communicate with the said passage-way between the ports 36 and 37 and the ports 32 discharge into the said passage-way between the ports 34 and 35.

The operation of my improved lubricator is as follows: The shaft C is rotated. Power is transmitted from the shaft C to the shaft B through the medium of the pinion e and the gear b. The receptacle a is charged with grease or lubricant (not shown) by removing the cap D and the head G, whereupon the head G is introduced into the chamber a and the cap D is replaced. The head G is prevented from rotation with the shaft B, as hereinbefore described, so that the head G during the rotation of the shaft B will descend and exert pressure upon the grease or lubricant contained within the chamber a, and thereby force lubricant through the ports 28 and 32 into the interior passage-way 20 of the shaft C and thence into the ports 34, 35, 36, and 37. As already indicated, the ports 34, 35, 36, and 37 discharge successively during the rotation of the shaft C, and consequently lubricant is adequately, positively, and uniformly fed to the different ducts 24, 25, 26, and 27 during each complete rotation of the said shaft.

It will be observed that by the construction hereinbefore described the shaft B and the

head G are free to be removed from the chamber a upon the removal of the cap D. The shaft B and its gear b and the head G are together lifted from the chamber a when the 5 said head has descended into its lowermost position within the said chamber.

The head G to facilitate its removal from the shaft B is divided centrally and longitudinally of its sleeve g into halves or sections 10 hinged together at the bottom and adjacent the joint between the said sections. Preferably each section of the head G is provided at its under side with ears 40, which are horizontally pivoted, as at 42, to the ears of the other 15 section of the said head. By this construction it will be observed that the sleeve g of the head G is when the said head is in the chamber a held in operative engagement with the shaft B by the surrounding wall of the 20 said chamber; but when the shaft B and head G are removed from the receptacle A, as shown in Fig. 2, the two sections of the head G are no longer held closed together by the said wall and tilt downwardly by gravity, so 25 as to laterally open the sleeve g, and thereby become disengaged from the screw-threads of the shaft B and render the said head free to be lifted from the said shaft. In replacing the shaft B and head G within the receptacle 30 A the shaft B is first placed in position with its gear b in mesh with the pinion c, whereupon the chamber a is charged with lubricant, and thereupon the head G is applied. The shaft B extends a suitable distance above the 35 upper end of the receptacle A and above the strip 17 and is preferably screw-threaded from its lower end upwardly to and above the said strip 17 to accommodate the placing of the head G with threads of the sleeve g in engagement 40 with threads on the shaft preparatory to the engagement of the recess 18 during the application of the said head with the aforesaid strip 17, and the head G having been operatively mounted on the shaft B is adjusted 45 circumferentially to bring its recess 18 opposite the upper end of the strip 17 and held in the required adjustment until the said recess during the lowering of the said head has engaged with the said strip 17, whereupon the 50 cap D is applied. The central portion of the cap bulges upwardly, as shown in Fig. 1, to accommodate the extension of the shaft B the desired distance above the strip 17.

What I claim is—

55 1. A lubricator comprising an upright receptacle provided, at its lower end, with boxes arranged a suitable distance apart and in line endwise; a shaft having bearing in the boxes and provided interiorly with a passage-way 60 which extends longitudinally of the shaft and is in communication with the interior chamber of the receptacle, with the surrounding wall of the passage-way provided with ports arranged a suitable distance apart longitudinally of the shaft; means for conducting lu- 65

bricant from the ports, and lubricant-feeding means for exerting pressure upon a body of lubricant within the aforesaid chamber, which lubricant-feeding means is operatively connected with the shaft.

70

2. A lubricator comprising an upright receptacle provided, at its lower end, with boxes arranged a suitable distance apart and in line endwise; a shaft having bearing in the boxes and provided interiorly with a passage-way 75 which extends longitudinally of the shaft and is in communication with the interior chamber of the receptacle, with the surrounding wall of the passage-way provided with ports arranged at suitable intervals circumferentially of the shaft and also spaced longitudinally of the shaft; means for conducting lubricant from the ports; and a lubricant-feeding head which is arranged to exert pressure upon lubricant within the aforesaid chamber 80 and operatively connected with the shaft.

85

3. A lubricator comprising an upright receptacle provided, at its lower end, with a shaft having an interior passage-way which extends longitudinally of the shaft and is in 90 communication with the interior chamber of the receptacle, with the surrounding wall of the passage-way provided with ports arranged at suitable intervals circumferentially of the shaft and also spaced longitudinally of the 95 shaft; discharge-ducts for conducting lubricant from the different ports respectively, and a lubricant-feeding head arranged to exert pressure upon lubricant within the aforesaid chamber and operatively connected with the shaft, and the arrangement of the parts being such that during the rotation 100 of the shaft the aforesaid ports shall come into registry successively with the respective discharge-ducts.

105

4. A lubricator comprising an upright receptacle provided, at its lower end, with a plurality of discharge-ducts arranged a suitable distance apart and in line laterally; a shaft extending across the inner ends of the 110 ducts and provided interiorly with a passage-way which extends longitudinally of the shaft and is in communication with the interior chamber of the receptacle, which shaft is provided in the surrounding wall of the said passage-way with as many ports as there are aforesaid ducts, which ports are spaced longitudinally and circumferentially of the shaft and arranged to communicate with the different aforesaid ducts respectively during the 115 rotation of the shaft, and a lubricant-feeding head arranged to exert pressure upon the lubricant in the aforesaid chamber and operatively connected with the aforesaid shaft.

120

5. A lubricator comprising an upright receptacle provided with several discharge-ducts arranged a suitable distance apart laterally; a shaft extending across the inner ends of the ducts and provided interiorly with a passage-way which extends longitudinally of 125 130

- the shaft and is in communication with the interior chamber of the receptacle, which shaft is provided in the surrounding wall of the said passage-way with as many ports as 5 there are aforesaid ducts, which ports are spaced longitudinally and circumferentially of the shaft and arranged to communicate with the different aforesaid ducts respectively during the rotation of the shaft; means for 10 preventing endwise displacement of the shaft, and a lubricant-feeding head arranged to exert pressure upon the lubricant in the aforesaid chamber and operatively connected with the shaft.
- 15 6. A lubricator comprising an upright receptacle provided, at its lower end, with downwardly-discharging ducts arranged a suitable distance apart laterally; a shaft extending across the inner ends of the ducts and provided 20 interiorly with a passage-way which extends longitudinally of the shaft and is in communication with the interior chamber of the receptacle; a box affording bearing to the shaft and arranged centrally of the lower end of the receptacle; two boxes affording bearing to the shaft and arranged adjacent opposite ends respectively of the central box, and a lubricant-feeding head arranged to exert pressure upon the lubricant in the aforesaid chamber and operatively connected with the aforesaid shaft, 25 and the shaft being provided in the surrounding wall of its aforesaid passage-way with as many ports as there are ducts, which ports are arranged as required to render them capable 30 of communicating with the different ducts respectively during the rotation of the shaft.
7. A lubricator comprising an upright receptacle provided, at its lower end, with a shaft which is arranged in a horizontal plane and 40 has an interior passage-way extending longitudinally of the shaft and communicating with the interior chamber of the receptacle; a box affording bearing to the shaft and arranged centrally of the lower end of the receptacle; two boxes affording bearing to the shaft and arranged adjacent opposite ends respectively of the central box; a lubricant-feeding head arranged to exert pressure upon the lubricant in the aforesaid chamber and operatively connected with the aforesaid shaft, 45 and downwardly-discharging ducts formed in the bottoms of the aforesaid boxes, and the shaft being provided in the surrounding wall of its aforesaid passage-way with as many ports as 50 there are ducts, which ports are arranged as required to render them capable of communicating with the different ducts respectively during the rotation of the shaft.
8. A lubricator comprising an upright receptacle provided, at its lower end, with a plurality of downwardly-discharging ducts arranged a suitable distance apart laterally; a shaft extending across the inner ends of the ducts and provided interiorly with a passage- 60 way which extends longitudinally of the shaft 65

and is in communication with the interior chamber of the receptacle, which shaft is provided, in the surrounding wall of its said passage-way, with as many ports as there are aforesaid ducts, which ports are arranged to 70 communicate with the different aforesaid ducts respectively during the rotation of the shaft; a box affording bearing to the shaft and arranged centrally of the lower end of and integral with the receptacle; two boxes arranged 75 in line endwise with and a suitable distance from opposite ends respectively of the central box and integral with the receptacle, and a lubricant-feeding head arranged to exert pressure upon the lubricant in the aforesaid 80 chamber and operatively connected with the aforesaid shaft.

9. A lubricator comprising an upright receptacle provided, at its lower end, with a plurality of discharge-ducts arranged a suitable 85 distance apart laterally; a shaft extending across the inner ends of the ducts and provided interiorly with a passage-way which extends longitudinally of the shaft, which shaft is provided, in the surrounding wall of 90 its said passage-way, with as many ports as there are aforesaid ducts, which ports are arranged to communicate with the different aforesaid ducts respectively during the rotation of the shaft; a box affording bearing to the shaft and arranged centrally of the lower end of the receptacle; two boxes arranged in line endwise with and a suitable distance from opposite ends respectively of the central box and integral with the receptacle, and a lubricant-feeding head arranged to exert pressure 95 upon the lubricant in the aforesaid chamber and operatively connected with the aforesaid shaft, and the said chamber being enlarged downwardly around the shaft between the 100 central box and the end boxes, and the said downward enlargements of the said chamber communicating with the aforesaid passage-way.

10. A lubricator comprising an upright receptacle provided, at its lower end, with ducts arranged a suitable distance apart laterally; a shaft extending across the inner ends of the ducts and provided interiorly with a passage-way which extends longitudinally of the shaft 110 and is in communication with the interior chamber of the receptacle, which shaft is provided, in the surrounding wall of its said passage-way, with as many ports as there are aforesaid ducts, which ports are arranged to 115 communicate with the different aforesaid ducts respectively during the rotation of the shaft; an externally-screw-threaded upright shaft arranged centrally of the aforesaid chamber and intergeared with the first-mentioned shaft; 120 a lubricant-feeding head arranged to exert pressure upon the lubricant in the aforesaid chamber and having a centrally-located sleeve provided with interior screw-threads engaging with screw-threads on the upright shaft, 125 130

and means for preventing turning of the said head with the upright shaft during the rotation of the shaft.

11. A lubricator comprising an upright receptacle provided, at its lower end, with ducts arranged a suitable distance apart laterally; a shaft extending across the inner ends of the ducts and provided interiorly with a passage-way which extends longitudinally of the shaft 10 and is in communication with the interior chamber of the receptacle, which shaft is provided, in the surrounding wall of its said passage-way with as many ports as there are aforesaid ducts, which ports are arranged to 15 communicate with the different aforesaid ducts respectively during the rotation of the shaft; a box affording bearing to the shaft and arranged centrally of the lower end of the receptacle; an externally-screw-threaded upright shaft arranged centrally of the aforesaid chamber and resting upon the said box and intergeared with the first-mentioned shaft; a lubricant-feeding head arranged to exert pressure upon the lubricant in the aforesaid 20 chamber and having a centrally-located sleeve provided with interior screw-threads engaging with screw-threads on the upright shaft, and means for preventing turning of the said head with the upright shaft during the rotation of the shaft. 25

12. A lubricator comprising an upright receptacle provided, at its lower end, with ducts arranged a suitable distance apart laterally; a shaft extending across the inner ends of the ducts and provided interiorly with a passage-way which extends longitudinally of the shaft and is in communication with the interior chamber of the receptacle, which shaft is provided, in the surrounding wall of its said passage-way, with as many ports as there are aforesaid ducts, which ports are arranged to 30 communicate with the different ducts respectively during the rotation of the shaft; a box affording bearing to the shaft and arranged centrally of the lower end of the receptacle; an externally-screw-threaded upright shaft arranged centrally of the aforesaid chamber and resting upon the said box and intergeared with the first-mentioned shaft; lateral bearings for the ends of the upright shaft; a lubricant-feeding head arranged to exert pressure upon the lubricant in the aforesaid chamber and having a centrally-located sleeve provided with interior screw-threads engaging with screw-threads on the upright shaft, and means for preventing turning of the said head with the upright shaft during the rotation of the shaft. 35

13. A lubricator comprising an upright receptacle provided, at its lower end, with ducts arranged a suitable distance apart laterally; a shaft extending across the inner ends of the ducts and provided interiorly with a passage-way which extends longitudinally of the shaft 40 and is in communication with the interior

chamber of the receptacle, which shaft is provided, in the surrounding wall of its said passage-way, with as many ports as there are aforesaid ducts, which ports are arranged to communicate with the different ducts respectively during the rotation of the shaft; an externally-screw-threaded upright shaft arranged centrally of the aforesaid chamber; a bevel-gear on the lower end of the last-mentioned shaft; a bevel-pinion meshing with the 45 said gear and operatively mounted on the first-mentioned shaft; a lubricant-feeding head arranged to exert pressure upon the lubricant in the aforesaid chamber and having a centrally-located sleeve provided with interior screw-threads engaging with screw-threads on the upright shaft, and means for preventing turning of the said head with the upright shaft during the rotation of the shaft. 50

14. In a lubricator, the combination, with 55 an upright receptacle having an outlet at its lower end, of an externally-screw-threaded upright shaft arranged centrally of the interior chamber of the receptacle and extending from the lower end to the upper end of 60 the receptacle; means for rotating the shaft; a cap or cover closing the receptacle at the upper end and affording lateral bearing to the shaft; means for supporting the lower end of the shaft; a lubricant-feeding head arranged 65 to exert pressure upon the lubricant in the aforesaid chamber and having a centrally-located sleeve provided with interior screw-threads engaging with screw-threads on the upright shaft, which head is provided with a 70 recess 18, and a vertically-arranged strip 17 secured to the surrounding wall of the aforesaid chamber and engaging the said recess. 75

15. In a lubricator, the combination, with 80 an upright receptacle provided, at its lower end, with an outlet, of an externally-screw-threaded upright shaft arranged centrally of and extending above the interior chamber of the receptacle; means for rotating the shaft; a cap or cover closing the receptacle at the 85 upper end and having an upwardly-bulged central portion extending over the shaft and having a depending member affording lateral bearing to the shaft; means affording bearing to the shaft at the lower end of the 90 shaft; a lubricant-feeding head arranged to exert pressure upon the lubricant in the aforesaid chamber and having a centrally-located sleeve provided with interior screw-threads 95 engaging with screw-threads on the upright shaft, and means for preventing turning of the said head. 100

16. In a lubricator, the combination, with 105 an upright receptacle provided, at its lower end, with an outlet, of an externally-screw-threaded upright shaft arranged centrally of the interior chamber of the receptacle; means for rotating the shaft; a lubricant-feeding head arranged to exert pressure upon the lubricant in the aforesaid chamber and having 110

- a centrally-located sleeve provided with interior screw-threads engaging with screw-threads on the shaft, and means for preventing turning of the said head with the shaft 5 during the rotation of the shaft, and the said head being divided centrally and longitudinally of the sleeve into two sections hinged together at the bottom, substantially as and for the purpose set forth.
10. 17. In a lubricator, the combination, with an upright receptacle provided, at its lower end, with an outlet, of an externally-screw-threaded shaft arranged vertically and centrally of the interior chamber of the receptacle; means for rotating the shaft; a lubricant-feeding head arranged to exert pressure upon the lubricant in the aforesaid chamber and having a centrally-located sleeve provided with interior screw-threads engaging with screw-threads on the shaft, and means for preventing turning of the said head with the shaft 15 during the rotation of the shaft, and the said head being divided centrally and longitudinally of the sleeve into two sections provided, at their under sides and adjacent to the joint from between them, with depending ears horizontally pivoted together.
18. In a lubricator, the combination, with an upright receptacle provided, at its lower end, with an outlet, of an externally-screw-threaded shaft arranged vertically and centrally of the interior chamber of the receptacle; means for rotating the shaft; a lubricant-feeding head arranged to exert pressure 20 upon the lubricant in the aforesaid chamber and having a centrally-located sleeve provided with interior screw-threads engaging with screw-threads on the shaft, and means for preventing turning of the said head with the shaft 25 during the rotation of the shaft, and the said head being divided longitudinally of the sleeve into sections.
19. A lubricator comprising an upright receptacle provided, at its lower end, with ducts arranged a suitable distance apart laterally; a shaft extending across the inner ends of the ducts and provided interiorly with a passage-way which extends longitudinally of the shaft and is in communication with the interior 30 chamber of the receptacle, which shaft is provided, in the surrounding wall of its said passage-way, with as many ports as there are aforesaid ducts, which ports are arranged to communicate with the different ducts respectively during the rotation of the shaft; means for operating the said shaft, and means for exerting pressure upon the lubricant in the aforesaid chamber.
20. A lubricator comprising an upright receptacle provided, at its lower end, with ducts arranged a suitable distance apart laterally; a shaft extending across the inner ends of the ducts and provided interiorly with a passage-way which extends longitudinally of the shaft 35 and is in communication with the interior
- chamber of the receptacle, which shaft is provided, in the surrounding wall of its said passage-way, with as many ports as there are aforesaid ducts, which ports are arranged to communicate with the different ducts respectively during the rotation of the shaft; means affording bearing to the said shaft; an externally-screw-threaded upright shaft arranged centrally of the aforesaid chamber above and intergeared with the first-mentioned shaft; bearings for the upright shaft; a lubricant-feeding head arranged to exert pressure upon the lubricant in the aforesaid chamber and having a centrally-located sleeve provided with interior screw-threads engaging with screw-threads on the upright shaft, and means for preventing turning of the said head with the upright shaft during the rotation of the shaft.
21. A lubricator comprising an upright receptacle provided, at its lower end, with a plurality of discharge-ducts arranged a suitable distance apart laterally; a shaft extending across the inner ends of the ducts and provided interiorly with a passage-way which extends longitudinally of the shaft, which shaft is provided, in the surrounding wall of its said passage-way, with as many ports as there are aforesaid ducts, which ports are arranged to communicate with the different aforesaid ducts respectively during the rotation of the shaft; a box affording bearing to the shaft and arranged centrally of the lower end of the receptacle; two boxes affording bearing to the shaft and arranged in line endwise with and a suitable distance from opposite ends respectively of the central box; means for operating the shaft, and means for exerting pressure upon the lubricant in the aforesaid chamber, and the said chamber being enlarged downwardly around the shaft between the central box and the end boxes, and the said downward enlargements of the said chamber communicating with the aforesaid passageway.
22. A lubricator comprising an upright receptacle provided, at its lower end, with ducts arranged a suitable distance apart laterally; a shaft extending across the inner ends of the ducts and provided interiorly with a passage-way which extends longitudinally of the shaft and is in communication with the interior chamber of the receptacle; boxes affording bearing to the shaft, and a lubricant-feeding head arranged to exert pressure upon the lubricant in the aforesaid chamber and operatively connected with the shaft, and the shaft being provided in the surrounding wall of its aforesaid passage-way with as many ports as there are ducts, which ports are arranged as required to render them capable of communicating with the different ducts respectively during the rotation of the shaft.
23. A lubricator comprising an upright receptacle provided with several discharge-ducts arranged a suitable distance apart laterally; a lubricant-feeding head arranged to exert pres-

sure upon the lubricant in the receptacle; means for actuating the said head endwise of the receptacle, and means whereby lubricant is discharged successively from the different 5 ducts respectively during the downward movement of the aforesaid head within the receptacle.

In testimony whereof I sign the foregoing specification, in the presence of two witnesses, this 7th day of April, 1904, at Cleveland, Ohio. 10

WILLIAM A. HATCHER.
